CLAIM

The ornamental design for a dog vest with pockets, as shown and described.

DESCRIPTION

FIG. 1 is a left front perspective view showing my ornamental design of a dog vest with pockets;

FIG. 2 is a right rear perspective view thereof;

FIG. 3 is a front view thereof;

FIG. 4 is a rear view thereof;

FIG. 5 is a right side view thereof;

FIG. 6 is a left view thereof;

FIG. 7 is a top view thereof;

FIG. 8 is a bottom view thereof;

FIG. 9 is a top flat view thereof;

FIG. 10 is a bottom flat view thereof; and,

FIG. 11 is a right side view thereof.

In FIGS. 1 to 11 the dashed lines on the dog vest with pockets represent seams and form no part of the claimed design. In FIG. 11 the dashed lines showing the dog illustrate environment only and form no part of the claimed design.
